CLAIM

The ornamental design for a modular adherence monitor for attachment to an inhaler, as shown and described.

DESCRIPTION

FIG. 1 is a side perspective view of a modular adherence monitor for attachment to an inhaler;

FIG. 2 is a bottom perspective view of a modular adherence monitor for attachment to an inhaler;

FIG. 3 is a back perspective view of the modular adherence monitor for attachment to an inhaler;

FIG. 4 is a top perspective view of the modular adherence monitor for attachment to an inhaler;

FIG. 5 is another bottom perspective view of the modular adherence monitor for attachment to an inhaler;

FIG. 6 is a left side elevation view of the modular adherence monitor for attachment to an inhaler;

FIG. 7 is an opposite side view of the modular adherence monitor for attachment to an inhaler;

FIG. 8 is front view of the modular adherence monitor for attachment to an inhaler;

FIG. 9 is a back view of the modular adherence monitor for attachment to an inhaler;

FIG. 10 is a top view of the modular adherence monitor for attachment to an inhaler; and,

FIG. 11 is a bottom view of the modular adherence monitor for attachment to an inhaler.

In all of the figures, the broken lines having a short dash pattern show an inhaler, and form no part of the claimed design.
